[57] CLAIM

The ornamental design for a trigger lock for a fuel pump nozzle, as shown and described.

DESCRIPTION

FIG. 1 is a side elevational view of a trigger lock for a fuel pump nozzle showing my new design;

FIG. 2 is a perspective view;

FIG. 3 is a front elevational view, the opposite side being a mirror image;

FIG. 4 is an end elevational view;

FIG. 5 is end elevational view of the side opposite that shown in FIG. 4;

FIG. 6 is a top plan view; and,

FIG. 7 is a bottom plan view.

The broken line showing of a gasoline pump nozzle is for illustrative purposes only and forms no part of the claimed design.
